BULLDOZER

Earl B. Maloon, Arcadia, and Willis H. Yount, Alhambra, Calif., assignors to Southwest Welding & Mfg. Co., Alhambra, Calif., a corporation of California

Application May 4, 1943, Serial No. 485,594

4 Claims. (Cl. 37—144)

This invention relates to a power scraper or pusher of the type known popularly as a "bulldozer."

While the improvement may be applied to any type of power vehicle, in the present specification it is described as applied to a tractor of the track laying type.

In this kind of implement the bulldozer bowl or pusher head is located at the front end of the vehicle, and is capable of being adjusted to any desired level.

One of the objects of this invention is to provide simple means for supporting and adjusting the height of the bulldozer head constructed in such a way that the supporting forces will be imparted to the track frame of the vehicle at a point well within the wheel base, or track base, so that these forces will not rock, or tip, the vehicle up or down at its ends.

Another object of the invention is to provide a support for the bulldozer head, which will enable the same to move up and down in a substantially straight line so that the inclination of the scraper blade or knife at the lower edge of the bulldozer, will present itself to the ground at substantially the same inclination.

Further objects of the invention will appear hereinafter.

The invention consists in the novel parts and combination of parts to be described hereinafter, all of which contribute to produce an efficient bulldozer.

A preferred embodiment of the invention is described in the following specification, while the novelty of the invention is pointed out in the appended claims.

In the drawings:

Fig. 1 is a side elevation of an embodiment of this invention as applied to a track laying type of tractor.

Fig. 2 is a plan of the construction illustrated in Fig. 1.

Fig. 3 is a vertical section on a larger scale taken about on the line 3—3 of Fig. 1.

In the drawings, 1 indicates the main frame of a vehicle, for example, a track laying tractor having side tracks 2 which are provided with the usual spurs 3 that dig into the ground and enable the tractor to exert a great tractive effort to push the bulldozer head 4 forwardly. This bulldozer head may be of any common construction such as that illustrated, and extends in the usual manner, completely across the front end of the implement. At each side the bulldozer head 4 is provided with a rearwardly extending side arm

5, and these arms extend a long way back and preferably to a point near the center of the rear wheels 6 of the tracks. The roller frame 1a on which the rollers for the tracks are guided, includes a side bar or frame member 7 which is disposed in a substantially horizontal position, and which is preferably formed of two parallel channel members with their webs vertical, and with flanges 8 at their upper and lower edges. Between the flanges 8 of the outboard channel we mount a block 9 on which the rear ends of the arms 5 are supported, preferably by means of pins 10 that project outwardly from the outer sides of the blocks 9. In this connection it should be understood that the construction at both sides of the tractor is identical. The detail of the connection to the pins 10 is relatively unimportant, but as illustrated, and in order to resist any force tending to move the rear ends of the arms laterally, we prefer to form the pins 10 with heads at each end and clamp the arms on the reduced waist or neck 11 between these heads. (See Fig. 2.) As illustrated, we provide a removable rear block or cap 12 that is clamped up by bolts 13 against the forward bearing member 14 at the rear ends of the arms.

The upper portion of the bulldozer head or bowl 4 is preferably braced to the side arms by means of a diagonal brace 15 located at each side; also by horizontal diagonal braces 15a as shown in Fig. 2.

Above the main frame we provide a forward boom 16, and toward the rear of the main frame we provide a substantially similar rear boom 17. These booms are preferably held in an inclined position with their lower ends supported at an intermediate point, or points, on the roller frame 1a with respect to its length in a fore-and-aft direction. In the present instance, we provide two brackets or bracket stanchions 18 and 19, the lower ends of which are attached to the top of the roller frame above the channels 7 at each side; and these brackets or stanchions extend up to about the level of the tractor floor 20. As illustrated in Fig. 2, each boom comprises a cross-head such as the cross-heads 21 and 22, each cross-head being rigidly connected to side forks 16a and 17a. These forks extend downwardly and are supported on the upper ends of the bracket stanchions 18 and 19 preferably as indicated. In making this connection, the lower end of each fork is provided with a head piece 23 which is in the form of a stout bar welded or otherwise secured to the adjacent portion of the fork. Each of these head pieces 23 at its

inner end, fits in between side plates 24 between which they are secured preferably by means of through pins 25. Each head piece lies substantially in a fore-and-aft plane.

The upper ends of the booms are preferably connected by a longitudinal stringer 26 through the medium of substantially vertical gusset plates 27 rigid with the stringer at each end, and these gusset plates 27 overlap similar gussets 28 attached to the cross-heads of the booms; and these gussets 27 and 28 are attached together preferably by through pins 29 as shown. The upper end of the rear boom 17 is preferably anchored to the main frame by means of a link 30, the lower end of which is connected by a pin 31 or other suitable connection to the main frame, or preferably to a drum frame 32 that extends rearwardly from the main frame, and carries a drum 33 over which the cable 33a passes for taking it up or paying it out. This cable passes over sheaves 34 and 35 located respectively, adjacent the upper end of the forward boom and the upper end of the rear boom. The sheave 34, if desired, may be in the form of a double sheave or triple sheave to enable the cable to be disposed in a fall 36, the lower loop of which passes around sheaves in the lower block 37 that is pivotally attached to the upper side of the bulldozer head.

The drum 33 is of course reversible and controllable from the driver's seat 38 by means of operating connections such as the lever 39. The upper end of the bracket stanchions 18 and 19 are also preferably connected by a link 40 located at each side.

The fixed end of the cable beyond the fall 36 may be secured in a clamp 41 adjacent to the upper sheave or sheaves 34.

It will be evident that the tension in the cable develops compressive forces in the booms, and the tension in the fall 36, tending to swing the forward boom downwardly, is of course resisted by the link 30 at the rear. The compressive forces in the booms of course are transmitted to the brackets 18 and 19 which deliver this load to the top of the roller frame, including the side frame bars 7.

A portion of the weight of the bulldozer head 4, and of course the horizontal thrust of the earth being moved by the bulldozer, is imparted to the side pins 10 near the rear of the tractor frame. The bulldozer preferably has an inclined main plate 42 which tends to incline this thrust in a downward direction, and this is desirable as tending to hold the rear end of the tractor frame down to its proper level. All of these forces developed, tend to maintain the tractor frame on an "even keel."

Fig. 3 illustrates how the horizontal extension or foot 18a or 19a of each bracket stanchion is seated on the top of each side beam or roller frame 1a. Each bracket stanchion is preferably formed with a goose-neck 18b or 19b that projects inboard for supporting the lower ends of the A frames or booms 16 and 17. This brings the vertical load line on the pins 24 and 25 well inboard and over the track 2, which is very advantageous.

When the booms 16 and 17 are supporting a load, the compression forces that are developed in them, are of course imparted to the brackets 18 and 19, and the horizontal components of these forces develop compression forces in the links 40. These links therefore act as strut links. By attaching the ends of the strut links

40 to the bracket stanchions 18 and 19, with pins that are distinct and separate pins from the pins that are employed for attaching the lower ends of the booms to these stanchions, we are enabled to bring the direction of thrust of the forks 16a and 17a in line with the strut links 40. This is most advantageous because it relieves the stanchions of any substantial torsional forces acting in a horizontal plane. And it is also advantageous because the thrust forces acting against the pins, can be resisted by a bearing for the pin on each side of the point of application of the thrust force.

When the tractor is moving, the usual leaf spring 16 resists the up-thrusts developed toward the forward end of the roller frame, which of course pivots in the usual way around the track sprocket axle 6a.

20 Removable pins or bolts are employed for making all the connections between the parts of the superframe. This facilitates shipping the superframe in a "knock-down" condition with the tractor.

Also by reason of the great distance from the bulldozer head to the pins 10 about which it swings, the radius to the plate 42 is so great that the head moves up or down in practically a straight line.

Many other embodiments of the invention may be resorted to without departing from the spirit of the invention.

What we claim is:

35 1. In an implement of the kind described, the combination of a track laying type tread at each side of the implement, a roller-frame on which the tread is mounted and including a substantially horizontal frame bar located respectively at each outboard side of the treads, a pair of stanchion brackets on each side spaced from each other in a fore-and-aft direction supported on each frame bar and extending upwardly therefrom, the upper ends of the brackets having extensions projecting inboard and over the upper runs of the tread, a bulldozer head located forwardly on the implement, having side arms pivotally supported on the side bars, a forward boom for the bulldozer head with side members pivotally supported on the said inboard extensions 45 50 55 of the forward bracket stanchions, a rear boom having forks mounted on the rearmost stanchion brackets, a tie bar connecting said booms, a strut connecting one of said booms to said implement, sheaves at the extremities of said booms and said bulldozer head, a hoist unit at the rear end of said implement, and a cable for lifting said bulldozer head passing over said sheaves and connected with said hoist.

2. An implement of the kind described, comprising: a main frame and a roller-frame; a bulldozer head disposed forwardly of the main frame and having side arms extending rearwardly therefrom and located on opposite sides of said roller-frame; means for supporting the rear portions of said arms on said roller-frame so as to permit the bulldozer head to swing up or down at the front and adjacent the ground level; a super-frame located above said main frame, including a bifurcated forward boom and a bifurcated rear boom, each of said booms comprising forks extending respectively toward the sides of said roller-frame; a pair of bracket stanchions located at each side of the implement, spaced from each other in a front-and-rear direction, pins connecting the lower ends of said forks with said bracket stanchions; a tie bar joining the extended por-

tions of said booms; a strut link anchoring one of said booms to the main frame; and a hoist including cable and sheave means connecting the extremities of said booms and said bulldozer head.

3. An implement according to claim 2, having track laying type treads; in which the upper ends of the bracket stanchions extend inboard; in which the lower ends of the forks are attached to the said bracket stanchions substantially in a front and rear vertical medial plane extending through the tread at each side.

4. An implement of the kind described, comprising: a main frame; a track laying type drive for the main frame, including an endless track tread located at each side of the main frame; a roller-frame including a substantially horizontal side beam located on the outboard side of each of said tracks; a bulldozer head at the forward end of the main frame having a side arm extending rearwardly at each side of the implement with means for pivotally supporting the said side arms adjacent their rear ends; a forward boom having side forks disposed in an inclined position and extending forwardly over the forward end 25

of the implement; a rear boom having side forks disposed in an inclined direction and extending rearwardly over the rear end of the main frame; a pair of bracket stanchions spaced from each other on each side secured on said roller-frame beams and extending upwardly therefrom; means connecting the upper ends of said bracket stanchions respectively with the forks of the forward boom and the forks of the rear boom; a longitudinal stringer disposed above the upper ends of the booms with means at each end located below the same for connecting the stringer to the upper ends of the booms; an anchor brace connecting at least one of said booms to said main frame; sheaves associated respectively with the ends of the stringer; a sheave block attached to the bulldozer head; a cable disposed in a fall at the forward end for supporting said block and extending over the first-named sheaves to the rear of the main frame; and a drum supported near the rear of the main frame for taking up and paying out the cable.
